Attorney

UNITED STATES PATENT OFFICE.

WINFRED L. SMITH, OF WESTBROOK, MAINE.

ADJUSTABLE TOOL HEAD.

Application filed May 28, 1925. Serial No. 33,544.

To all whom it may concern:

Be it known that I, WINFRED L. SMITH, a citizen of the United States, residing at Westbrook, in the county of Cumberland and State of Maine, have invented certain new and useful Improvements in Adjustable Tool Heads; and I do hereby declare the following to be a full, clear, and exact description of the invention, such as will enable others skilled in the art to which it appertains to make and use the same.

The invention relates to hand tools and particularly to the rake and hoe type of tool and has for its object the provision of means by which the rake or hoe head may be adjusted relatively to the handle to permit close approach to the wall of a building or the side of a curb stone or coping.

Another object of the invention is the provision of means by which the adjustment of the head may be expeditiously accomplished while the tool is in use and while it is in working position so that the proper angle may be readily accomplished to better perform the work and after the tool has been used with the head at an adjusted angle it may be returned to its former position and the work continue without changing the position of the handle.

The construction and operation and advantages of the invention will be described in detail hereinafter and will be found illustrated in the accompanying drawings in which—

Figure 1 is a side view of the improved tool showing it as a rake,

Figure 2, a top plan view showing the handle partly in section,

Figure 3, a sectional view on a plane indicated by the line 3—3 of Figure 1,

Figure 4, a sectional view on a plane indicated by the line 4—4 of Figure 1, and

Figure 5, a detail view of a hoe head arranged to be used on the tool handle.

In the drawings, similar reference characters will be used to designate corresponding parts throughout the several views.

The handle 1 of the improved tool is tubular as shown and has an extension 2 that is swivelly mounted thereon by means of ferrule 3 secured to the extension 2 by means of a rivet 4. 5 indicates a rod also secured to extension 2 by means of the rivet 4 and extending through the bore of the tubular

handle 1 and having its free end provided with threads 6 of a wide gauge, as shown, for the purpose hereinafter stated. 7 indicates a collar secured to rod 5 and engaging the free end of the handle 1 that is designed to prevent end motion of the part 2 relatively to the part 1 of the handle.

8 indicates a tapered sleeve secured to the free end of handle 1 and having secured in its outer end a ring 9 having prongs 10 extending therefrom and diverging downwardly and outwardly. The free ends of prongs 10 are pivotally secured to the tool head 11 by means of ears 12, the pivot pins 13 therefor being of a type that may be readily removed to permit quick changing of the tool head from one type to another.

14 indicates an arm extending from the tool head 11 intermediate of the ears 12 and having an upwardly curved portion that is pivotally secured to a rod 15 by means of a removable pin 16 of the same type as the pins 13 heretofore referred to. Rod 15 extends through an opening in the ring 9 into the interior of the sleeve 8 and has on its inner end a yoke 17 the cross head 18 of which is threaded to engage the threads 6 on the rod 5.

It will be apparent that in using the tool the angle of the head 11 may be quickly adjusted by turning the extension 2 relatively to the handle 1, the threaded connection of the cross head 18 with the end of the rod 5 moving the head 11 to change the angle of the head relatively to the handle.

In Figure 5 is shown a hoe head that is adapted for use with the handle in which the ears 12^a and the arm 14^a are shown riveted to the blade designated 20. In the adaptation of the invention I have shown in Figures 1, 2, and 3, the ears 12 and arm 14 are cast on the head but obviously as indicated in Figure 5 these parts may be made separate and riveted to the tool head if so desired.

What is claimed is:—

1. In a tool, a handle, a head pivotally engaging said handle, an extension of the handle swivelly mounted thereon, a rod secured to said extension and extending through the handle, another rod engaging the head, a yoke on the last mentioned rod, and threaded connection between said yoke and the first mentioned rod.

2. In a tool, a handle, prongs secured to and extending from one end of the handle, a head pivotally engaging said prongs, an extension of the handle swivelly mounted thereon, a rod secured to said extension and transversely through said handle, the free end of said rod being screw threaded, an-

other rod pivotally engaging said head, and a yoke on said rod and having a threaded aperture engaging the threads on the first 10 mentioned rod.

In testimony whereof I affix my signature.

WINFRED L. SMITH.
